UNITED STATES PATENT OFFICE.

CHARLES W. DAKE, OF CHICAGO, ILLINOIS.

ELECTRIC-LIGHT HOUSING.

Application filed October 27, 1924. Serial No. 745,949.

My invention relates to housings for electric lights particularly for use in connection with flood lights, headlights and the like wherein incandescent filaments of high intensity are used and wherein it is desirable to provide means for cooling the reflecting surface without permitting the introduction of outside air. One object of my invention is to provide a light housing wherein automatic circulation of the enclosed body of air may take place when the light is operated. In this connection attention is called to my copending application of even date herewith Serial No. 745,950. Other objects of my invention will appear from time to time in the course of the specification and claims.

My invention is illustrated more or less diagrammatically in the accompanying drawings, wherein—

20 Figure 1 is a front view;

Figure 2 is a back view with parts broken away and parts in section;

Figure 3 is a section along the line 3—3 of Figure 1.

25 Like parts are indicated by like characters throughout the specification and drawings.

A is a base or bracket adapted to be fastened to a suitable support in any desired method not here shown. This base has a central boss A¹ containing a screw A² on which is a lock nut A³. A⁴ is a bail or bracket mounted on the boss A¹ and held in position by the nut and screw, A³ and A² and a washer A⁵.

30 B is a metallic housing provided with trunnion bosses B¹ B¹ on opposed sides adapted to engage the ends of the bail A⁴. From these trunnions project screws B² associated with nuts B³ and washers B⁴ where- 40 by the housing may be clamped in adjusted position or made to swing as the case may be. The arrangement just described permits any desired adjustment of the axis of the beam of light and might be dispensed with if it were desired to use the light in a 45 fixed position when other suitable means for the housing might be used.

The housing is closed by a door comprising an annular ring C, having ears C¹ C¹ carrying a pivot pin C² in a pivot lug C³ on the housing and a slotted lug C⁴ engaging a screw C⁵ and thumb nut C⁶ on a lug C⁷ on the housing whereby the door may be firmly held in place and the packing ring C⁸ may be compressed to make an air tight closure. C⁹ is a translucent panel or lens provided

with a packing ring C¹⁰ and held in place in the door by means of spring clips C¹¹ and holding screws C¹².

60 The lower rear side of the housing B comprises an apertured spherical member D. In this spherical member is mounted a threaded sleeve D¹ having a spherical flange D² adapted to engage the inner surface of the spherical member D. Threaded on the sleeve D¹ is a lock sleeve D³ having a spherical flange D⁴ adapted to engage the outer surface of the member D so that when these two sleeves are threaded one on the other and tightened up, the spherical member D is gripped between the spherical flanges D² D⁴ 65 permitting adjusting movement of the sleeve D¹ about a center of rotation inside the housing at the point D⁵. D⁶ is a sleeve slid- 70 able in the sleeve D¹ and adapted to be held in longitudinal adjusted position by means of the set screw D⁷. This sleeve contains a socket for the electric light bulb D⁸ the current therefor passing up through the sleeve from the conductors D⁹. By this arrangement the electric light bulb may be moved longitudinally when the set screw D⁷ is released and may be swung in any desired 75 position about the point D⁶ when the sleeves are loosened.

80 E is a reflector support contained within the housing B. It has carried on it two bridge extensions E¹ E¹ extending laterally between it and the wall of the housing and vertically disposed. E² is a reflector contained within the support E and spaced therefrom as indicated, except about its periphery where a cushion ring E³ is interposed between them. E⁴ is a holding ring surrounding the periphery of the reflector support E and held in place by the screws E⁵ and adapted to hold the reflector in place in the housing. The reflector and the housing are both apertured as indicated adjacent the pivot point D⁵, thus making it possible to adjust the light in the reflector while still making it possible to use a very small opening through the reflector for the light socket.

85 The space between the reflector and the reflector housing is relatively thin and furnishes therefore the dead air space wherein the air movement is slight so as to protect the back of the housing from the heat of the incandescent filament. The corrugations E⁶ E⁷ in the back of the housing also 90 assist by cooling the rear wall of the hous- 95 ing.

100

110

ing. The result of this is that when the light is on the air in the front part of the housing is heated and tends to rise up and travel in the direction indicated by the arrows being cooled on its way down where it engages the inner side of the corrugated cool housing. The dead air space at the back of the reflector protects this air against the heat of the filament and thus there is a constant circulation of air in the direction indicated by the arrows. There will also be some circulation up through the body of the reflector between the light socket and the boundary of the perforations in the reflector. Such heated air will travel out as indicated by the arrows and join with the main stream.

The result of this is that the housing can be kept rigidly air tight and there will still be a sufficiently even circulation of air to keep the reflector cool enough to prevent damage to it, owing to the force of the heat circulating air as it passes from the hot filament to the cool back of the housing.

It will be evident that while I have shown in my drawings, an operative device, still many changes might be made in the size, shape and disposition of parts without departing materially from the spirit of my invention and I wish, therefore, that my showing be taken as in a sense diagrammatic.

I claim:

1. An electric light case comprising an hermetically sealed housing, a reflector support mounted in and out of contact with the walls thereof, a reflector carried by but spaced from the support to provide a dead air space, an electric light source in the housing and means for cooling the wall of the housing behind the reflector support, a support for the electric light source projecting inwardly through the reflector and the

reflector support, and adjustably mounted in the wall of the housing.

2. An electric light case comprising an hermetically sealed housing, a reflector support mounted in and out of contact with the walls thereof, a reflector carried by but spaced from the support to provide a dead air space, an electric light source in the housing and means for cooling the wall of the housing behind the reflector support, a ball and socket support for the electric light source projecting in part inwardly through the reflector and the reflector support, and adjustably mounted in the wall of the housing, the center of rotation of the ball and socket lying adjacent the periphery of the reflector.

3. An electric light case comprising an hermetically sealed housing, a reflector support therein, horizontal bridge elements extending across the housing between the wall thereof and the reflector support, the reflector support being carried by the bridge elements and out of contact with the walls of the housing and enclosing between it and the reflector a dead air space, the reflector contained within the support and out of contact therewith except at its periphery.

4. An electric light case comprising an hermetically sealed housing, a reflector support therein, horizontal bridge elements extending across the housing between the wall thereof and the reflector support, the reflector contained within the support and out of contact therewith except at its periphery, the back wall of the housing adjacent the reflector support being corrugated for cooling.

Signed at Chicago county of Cook and State of Illinois, this 23rd day of October, 1924.

CHARLES W. DAKE.
